(57) **CLAIM**

The ornamental design for an earbud receiver, as shown and described.

DESCRIPTION

FIG. 1 is a rear left 3/4 perspective view of a earbud receiver showing our ornamental design;

FIG. 2 is a rear view of the earbud receiver;

FIG. 3 is a front view of the earbud receiver;

FIG. 4 is a left side elevational view of the earbud receiver;

FIG. 5 is a right side elevational view of the earbud receiver;

FIG. 6 is a top elevational view of the earbud receiver; and,

FIG. 7 is a bottom elevational view of the earbud receiver.

The dashed lines are to show environment, and are not part of the claimed design.
